UNITED STATES PATENT OFFICE.

ANDREW LITTLE, OF NEW YORK, N. Y.

DESIGN FOR A FONT OF PRINTING-TYPES.

Specification forming part of Design No. **11,185**, dated May 6, 1879; application filed April 10, 1879.
[Term of patent 14 years.]

To all whom it may concern:

Be it known that I, ANDREW LITTLE, of the city, county, and State of New York, have invented and produced a new and original Design for a Font of Printing-Types, of which the following is a specification.

The nature of my design is clearly shown in the accompanying typographic impression, to which reference is made.

It consists of a script-letter of what may be termed the "back-hand" as distinguished from the "running-hand" style.

In the letters B, D, F, H, J, K, M, N, P, R, T, U, V, W, X, Y, and Z the upper left-hand portions terminate in the curve, as shown.

In the letters C, E, G, and L the upper right-hand portions of the letters terminate in the curve, as shown.

In the letters A, I, and S the lower left-hand portions of the letters terminate in the curve, as shown.

In the letters F, H, K, and T the lower left-hand portions of the letters gradually widen as they approach the light inclined lines projecting above and below them.

In the letters G, J, and Y these terminations are found at the bottom upon the left; but the light inclined lines project below only.

In the letters B, P, R, and W the lower terminations of the up-and-down portions upon the right gradually widen as they approach the light inclined lines projecting above them.

In the letters A, C, E, H, K, L, M, N, U, P, Q, R, X, and Z the light inclined lines are found at the lower right termination.

Both terminations of the K and X upon the right have the light inclined lines.

The cross portion of the A gradually widens as it extends from the right to the left, and is followed by the light inclined line projecting upward.

The rounding portions of the letters B, E, K, and R form a loop about centrally.

The cross portion of the F is composed of a light inclined line followed by the pendent gradually-widening termination, from the lower portion of which projects the light inclined line.

The upper right-hand portions of the M and N are formed by the light inclined lines followed by the gradually-widening portions, and these by the portions gradually widening as they approach the bottom.

In the P and K the upper right-hand portions are composed of the light inclined lines followed by the rounding portions, which gradually widen for a portion of their length and then become narrow, as shown.

The rounding portions of the O and Q gradually widen upon the upper right-hand and lower right-hand corners, and the tail of the Q is composed of the gradually-widening termination, followed by the light inclined line.

The up-and-down portions of the V are connected by the inclined line, as shown.

The upper portions of the W, following the up-and-down portion curved upon the left, are connected by the light inclined lines upon the left hand.

The cross portion of the Z gradually widens from the left to the right.

The upper right-hand portion of the S gradually widens as it approaches the light inclined line projecting upward.

In the figures the character of the design is preserved, the light inclined lines being found upon the right and left of the 1 and 4. Upon the right of the upper portion of the 5, upon the left of the upper portion of the 7, and upon the lower right-hand portion of the 2, the curved termination characterizing the 2, 3, 5, 6, and 9, while in the 8 and 0 the portions gradually widen upon the upper right hand and lower left hand.

In the lower case the light inclined lines are found upon the right of the a, c, d, e, g, h, i, j, k, l, m, n, q, r, t, u, x, and z, and upon the left of the b, d, f, g, h, i, j, k, l, m, n, p, r, s, t, u, x, y, and z, and the gradual widening of certain portions of the letters is maintained.

In the symbol & the central termination upon the right gradually widens as it approaches the light inclined line pendent below it.

The dollar-symbol has both terminations curved and widens centrally, and the lower portions of the comma, semicolon, and apostrophe terminate in the light inclined line.

Having now described my invention, what I claim as new is—

The design for a font of printing-types, substantially as described.

ANDREW LITTLE.
